UNITED STATES PATENT OFFICE.

ORLEY C. HOUGHTON, OF DAVENPORT, IOWA, ASSIGNOR TO BULLOCK TRACTOR COMPANY, OF CHICAGO, ILLINOIS, A CORPORATION OF ILLINOIS.

TRACTION-TRUCK.

1,142,169.

Specification of Letters Patent. Patented June 8, 1915.

Application filed June 23, 1913. Serial No. 775,272.

To all whom it may concern:

Be it known that I, ORLEY C. HOUGHTON, a citizen of the United States, and a resident of the city of Davenport, in the county 5 of Scott and State of Iowa, have invented a certain new and useful Improvement in Traction-Trucks; and I do hereby declare that the following description of my said invention, taken in connection with the accompanying sheets of drawings, forms a full, clear, and specific specification, which will enable others skilled in the art to which it appertains to make and use the same.

My invention relates generally to improvements in traction trucks, and it consists, essentially, in the novel and peculiar combination of parts and details of construction, as hereinafter first fully set forth and described and then pointed out in the claims.

20 In the drawings already referred to, which serve to illustrate my said invention more fully, Figure 1 is a side elevation of the same with certain parts removed. Fig. 2 is a plan thereof. Fig. 3 is a vertical transverse section in line 0 0 of Fig. 1. Fig. 4 is a similar section in line 1 1 of Fig. 1. Fig. 5 is an elevation of a detail of construction, and Fig. 6 a section thereof in line 2 2 of Fig. 5. Fig. 7 is an elevation of a roller tooth pinion used in connection with my device, certain parts being broken away and shown in section to better illustrate the internal construction. Fig. 8 is a section in line 3 3 of Fig. 7.

35 Like parts are designated by corresponding characters and symbols of reference in all the figures of the drawings.

40 In the design of traction trucks for farm engines, traction engines, and the like of the endless track laying type, conditions are met with that do not exist in any other class of machinery. First of all such a mechanism must be essentially "fool proof" by reason of the lack of care bestowed upon the same. 45 Secondly, it must have great strength, yet be light and possess great flexibility to overcome conditions of road or field.

50 My truck possesses all the necessary qualifications and I will now proceed to disclose the same by a reference to the drawings, in which A is the endless track chain, which may be of any preferred type of construction.

55 B is an inverted V-shaped frame, having at its apex hubs 1 and 2 extending horizon-

tally from the front and rear face thereof. These hubs have a common axial opening through the same for the free reception of a steel shaft 3, which shaft is fixed by means of pins 4 and 4^a, or otherwise in 60 journal bearings 5 and 5^a, located on the under side of opposite sills 6 and 6^a of a suitable tractor frame C.

On the shaft 3, at the outer end of hub 1, there is located an antifriction washer 7 65 and exteriorly of this a collar 8 which is fastened to said shaft by a pin 9 or similar means.

It will now be understood that shaft 3 extends beyond bearing 5^a as far as it does 70 beyond bearing 5, and that there is located on such extension another truck frame B and its appurtenances. Attention is also directed to the fact that the said truck frames are adapted to swivel in a vertical plane 75 about the axis of shaft 3 for purposes hereinafter referred to.

Declining from hubs 1 and 2 are heavily ribbed side frames 10 and 10^a extending in opposite directions as seen in Figs. 1, 9, and 80 10. At its outer end frame 10^a terminates in a heavy circular boss 11, which boss is axially and horizontally apertured for the reception therein of a tight fitting steel shaft 11^a, said shaft extending exteriorly of said 85 hub in both directions and being held rigidly in said hub by pins 12 or other fastening means.

Adapted to freely rotate on the forward extension of shaft 11^a there is located a 90 toothed sprocket wheel 13, which is prevented from withdrawing from said shaft by an antifriction washer 14 and a pinned collar 15. This sprocket is adapted to mesh 95 into the endless track chain A in an obvious manner.

100 Meshing into the teeth 13^a of sprocket 13 is a roller pinion 16 journaled on a shaft 17, which passes through a hub or boss 18 on frame 10^a to and beyond the rear side thereof. Adjacent the rear wall of said frame 10^a, on shaft 17, is fixed a sprocket 19, to which power is adapted to be transmitted by a suitable traction chain (not shown) from a source of power located on tractor 105 frame C. The inner free end of shaft 17, exterior of sprocket 19, is supported in a hub 20 of an integrally formed bracket 21 extending from hub 2 to boss 11 and the rear wall of frame 10^a, thus producing a firm and 110

rigid support for said shaft 17, pinion 16, and sprocket 19.

It will now be noted that the endless track-sprocket driving-pinion 16 being journaled in the frame 10^a, no amount of oscillation, vibration, or lateral sway of the truck frame B while in action will affect the mesh of the sprocket teeth 13^a with the roller pins of the pinion 16. Again, the shaft 17 being located so close to the axis of oscillation of said frame, no perceptible lengthening or shortening action will take place with respect to the driving chain (not shown) which actuates sprocket 19. These are important features and essentials of a successful and efficient truck of the class described.

At the free end of side frame 10 there is produced a large circular boss 22 possessed of external side ears 23 and 23^a which ears are tapped to receive tap bolts 24 and 24^a for purposes hereinafter disclosed. Said boss has a large, interior, axial circular core for the reception of a cylindrical hub 25, Figs. 5 and 6, of a socalled eccentric adjusting frame D. This frame comprises the hub 25 having a flange 26 on one end thereof, in which flange there are formed concentric slots 27 and 27^a, through which the tap bolts 24 and 24^a are adapted to be passed in order to clamp said eccentric adjusting frame D in any desired position within the range of the slots 27 and 27^a, to the circular boss 22.

Passing longitudinally through hub 25, eccentrically to the axis of said hub, there is a shaft 28 extending forwardly of the boss 22 and hub 25. Said shaft is fixed in hub 25 by a pin 28^a, or equivalent means, and freely embracing this shaft is a flat rimmed 40 idler wheel 29 Figs. 1 and 2, which wheel is in direct alinement with the sprocket wheel 13 and bears upon the endless track chain A as seen in Fig. 1.

It is now explained that endless track chain A is trained over wheel 29 and sprocket 13 and made endless, so that the lower run of said chain supports the truck frame B as a whole with all its appurtenances, while the upper run of the chain is supported by said wheel and sprocket in an obvious manner. Wheel 29 is prevented from withdrawal from shaft 28 by an anti-friction washer 30 and a pinned collar 31 on the shaft 28 as illustrated in Fig. 2.

55 After having been operated for some time there will be caused a slight stretch in the endless track chain A due to a slight reduction in diameter of the link pins 32 and a corresponding enlargement of the pin holes 33 Fig. 1, resulting in an undue sag on the upper run of the chain and a more or less side "flop" thereof while in action. To compensate for this extra length of chain there is provided the adjusting frame D hereinbefore described. Releasing the bolts 24,

24^a and then giving a few blows of a sledge applied in the proper direction to the flange 26 of said frame D, will rotate this eccentric adjusting frame and thus increase the distance between the shafts 11^a and 28 and thereby take up all slack in said chain, after which the tap bolts 24 and 24^a are tightened up to again rigidly retain frame D in position.

There is always a slight amount of sag in the upper run of the endless track chain A, and in order to support the same, there is provided an idler roller 34, journaled on a shaft 35, which shaft is supported in a forked arm 36. This arm is pivotal on a stud 37 fixed in frame 10 a short distance from hub 1. Set screws 38 passing through the web of arm 36 and bearing upon said hub 1 are employed to raise and lower idler 34 in a manner readily understood, for the purpose of raising the upper lap of the endless track chain as much as may be desired.

Depending in a vertical plane from side frames 10 and 10^a are heavily ribbed legs 39, 40, 41, each of which is possessed of a hub 42 at its lower extremity. In each of these hubs there is firmly fixed a forwardly extending horizontal shaft 43, on which shafts are adapted to freely revolve flanged rollers 44 and 44^a, the periphery of which rollers contact with the top surfaces 45 and 45^a of the endless track chain A, while the flanges thereof embrace the side walls 46 and 46^a of said chain. The greater proportion of the load supported by the truck B is carried by this plurality of rollers, the sprocket 13 and wheel 29 being intended more as a driver and driven means for the endless track, although they will, as a matter of course, bear a small portion of the load.

The outer ends of the shafts 43 of the bearing-rollers 44, 44^a, are supported by a semi-circular steel ribbed frame 47 having hubs 48 tightly embracing said shafts. This frame is firmly bolted to the ribbed legs 39, 40, 41, by means of bolts 49 tapped into bosses 50, extending out from and heavily ribbed to the legs 39, 40 and 41 as best seen in Figs. 3, 4, 10, and 11.

It will thus be seen that my traction truck 115 is self-contained in every respect. All parts subject to stress or strain are tied together by an integral casting, yet there is sufficient flexibility therein to permit of a certain amount of give to the parts under a sudden overload.

The pinion 16 employed to drive sprocket 13 is of peculiar construction especially adapted for the rough and severe service to which it is subjected when in action. It may briefly be described as follows: It comprises a central hub 60 Fig. 8 having an axial bore 61 and keyseat 62 fitting the shaft 17. This hub is formed integrally in the process of casting with parallel circular 130

flanges 63 and 64 in spaced relation, and these flanges are drilled with a plurality of concentric, registering holes 65 and 66, respectively, those in flange 64 being of 5 smaller diameter than the ones placed in flange 63. Into and through holes 65 are passed pins 67 there being passed over said pins, loosely fitting rollers 68, the length of which are equal to the space between the 10 flanges 63 and 64 less a slight clearance. One end of pins 67 is shouldered at 69 for passage through holes 66, exteriorly of which the pins are riveted over at 70. When so riveted home, the opposite end of these 15 pins are just flush with the exterior face of flange 63, at which end said pins are axially drilled at 71 for a portion of their length and then cross drilled at 72 to afford the entrance of a lubricant to the interior bore of 20 the rollers 68. These pins and rollers are all hardened to resist wear and reduce the friction between the parts and between the rollers themselves and the teeth 13^a of sprocket 13.

25 To introduce lubricant to the oil channels 71, there is first placed against the exterior face of flange 63 a punched annular gasket 73, the holes in which register with holes 71. And against this gasket is bolted by 30 bolts 74 a double walled circular metallic chamber 75. Wall 76 of this chamber is punctured with holes 77 registering with holes 71, and opposite wall 78 has an axial opening 79, into which is led an oil pipe 80 35 of an oil cup 81, which cup is conveniently located on truck frame B.

Oil chamber 75 is intended to be kept slightly less than half full of oil at all times, so that when the rollers 68 in the course of 40 the rotation of the pinion reach a point below the horizontal center line their interior surfaces will be flushed with oil passing through the oil passages 71 and 72.

While herein I have described the preferred construction of my traction truck, I 45 desire it understood that I may make such changes and alterations therein as would suggest themselves to the skilled mechanic and permitted under the doctrine of mechanical equivalents without falling outside 50 the spirit or scope of my invention.

Having thus fully described my invention I claim as new and desire to secure to myself by Letters Patent of the United States:

55 1. In a traction engine, the combination, of a main frame, an oscillating truck frame pivotally connected to said main frame, said truck frame including a substantially triangular member having at its apex a shaft 60 on which said truck frame is constructed to oscillate, said truck frame having downwardly-inclined members, there being at the ends of said inclined members bearings, shafts fixed in said bearings, a sprocket 65 wheel rotatably mounted on one of said

shafts, an idler wheel rotatably mounted on the other of said shafts, an endless track trained over said sprocket and said idler wheel, a bracket formed integrally with one of said inclined members at the rear side 70 thereof and connecting said end bearing to the bearing at the apex of said triangular frame, said bracket being in spaced relation to said inclined frame-member, a bearing in said bracket adjacent to said apex-bearing, 75 and a bearing in said inclined member in alinement with the bearing in said bracket, a driving shaft rotatably journaled in said bracket and said inclined member, a sprocket wheel affixed to said latter shaft between said 80 bracket and the inclined member, and a lantern pinion affixed to said shaft at the outer side of said truck frame and engaging said chain-sprocket, there being in the bearing for the idler track-chain wheel-shaft eccentrically disposed means for varying the distance between said sprocket and the idler 85 wheel.

2. In a tractor of the type described, a main frame, and a truck frame pivotally 90 connected to said main frame, said truck frame including a substantially triangular body having at its apex a shaft on which said truck frame is constructed to oscillate, said truck frame having downwardly ex- 95 tending members terminating in bearings, a shaft in each of said bearings, a sprocket wheel rotatably mounted on one of said shafts, and an idler wheel rotatably mounted on the other of said shafts, an endless track 100 trained over said sprocket and said idler wheel, and means for supporting the truck frame upon the lower run of said endless track, said latter means including vertically-disposed legs pending from the inclined 105 members of said truck frame, said legs terminating in bearings, a substantially semi-circular frame fixed to said legs in spaced relation, said semi-circular frame having bearings in alinement with the bearings on 110 said legs, shafts horizontally disposed in the latter bearings, and flanged bearing wheels mounted on said shafts constructed to rotate upon the upper surface of the lower run of 115 said endless track.

3. In a traction engine of the type described, the combination, of a main frame, a truck frame connected to said main frame, a driven sprocket and an idler wheel rotatably mounted in said truck frame, an endless 120 track trained over said sprocket and said idler wheel, and means for varying the distance between said sprocket and said idler wheel, said means including a centrally bored hub at one terminal of said truck 125 frame, a flanged hub, there being curved slots in said flange, a bore through said hub eccentric to the axis of rotation of said flanged hub, a shaft in the latter bore on which said idler wheel is constructed to 130

rotate, and means for movably securing said flanged hub to the hub at the terminal of said truck-member.

4. In a traction engine having an endless, self-laying track-band trained over a pair of spaced wheels, one of which, at least is a sprocket wheel, a lantern pinion constructed to engage said sprocket wheel, said lantern pinion comprising two annular disks in spaced relation, pins constructed to connect said disks, there being a central bore in each pin, and a cross-passage leading from the central bore to the periphery of said pin, a roller on each pin, an annular chamber at the flank of one of said annular disks, said chamber being of approximately the same diameter as said disk, there being in the wall of said chamber adjacent to the flank of said disk openings communicating with the central bores of said pins.
5. In a traction engine of the type described, having endless, self-laying track-band, a sprocket wheel over which said track-band is trained, a lantern pinion constructed to engage said sprocket wheel, said lantern pinion comprising two annular disks in parallel spaced relation, a series of pins constructed to connect said disks, there being in each pin a central bore and a radial passage leading from said central passage, a roller on each pin, a single annular chamber at the flank of one of said annular disks, there being in the wall of said chamber, openings communicating with all of the central bores of said pins.

6. In a traction engine, the combination with a chassis, a motor mounted on said chassis, one or more trucks constructed to support said chassis, a sprocket wheel at one end of said truck, a wheel at the other end of said truck, an endless traction band trained over the co-acting pair of said wheels, a lantern pinion constructed to engage the said sprocket wheel, and intermediate mechanism constructed to connect said motor to said lantern pinion to rotate said sprocket wheel directly by said lantern pinion, said lantern pinion including two circular disks in spaced relation, an axle on which said disks are mounted, and a series of pins concentric to the axis of said shaft, said pins performing the function of cogs for said pinion.
7. In a tractor having endless self-laying track-bands, a pair of wheels, one of which at least is a sprocket-wheel over which said self-laying track is trained, a motor on said tractor, a lantern pinion constructed to engage said sprocket-wheel, and intermediate mechanism constructed to connect said motor to said lantern pinion to rotate said sprocket-wheel directly by said lantern pinion, said lantern pinion including two circular disks in spaced relation, an axle on which said disks are mounted, and a series of pins concentric to the axis of said shaft, said pins performing the function of cogs for said pinion.
8. In a tractor of the type described, the combination, with a combined driven and driving sprocket-wheel, of a driving pinion for said sprocket-wheel, said pinion comprising a central hub and two annular flanges in parallel spaced relation, said hub and flanges being integrally formed, a series of apertures in each flange concentric to the axis of said hub, and in alined relation, a like series of pins fastened in one of said flanges and entering the opposing openings in the companion flange, and an anti-friction roller on each of said pins.

In testimony whereof I have hereunto set my hand in the presence of two subscribing witnesses.

ORLEY C. HOUGHTON.
